CLAMP FOR CONNECTING FILAMENTARY ARTICLES TO MOVING TRACTION ELEMENTS

Joseph E. Lodge, Baltimore, Md., assignor to Western Electric Company, Incorporated, New York, N. Y., a corporation of New York

Application July 7, 1949, Serial No. 103,486

1 Claim. (Cl. 24—85)

1

This invention relates to clamps for connecting filamentary articles to a moving traction element, and more particularly to clamps for connecting an insulating compound strip to an endless moving cable or the like.

In processing vulcanizable insulating or jacketing compounds used in the manufacture of electrical conductors the compound may be conveyed to conventional conductor insulating or jacketing apparatus in strip form after the various ingredients thereof are mixed in suitable mixing apparatus. In such a process the compound strip is passed through a suitable cooling device to reduce the temperature of the compound and prevent prevulcanization of the compound before it reaches the insulating or jacketing apparatus. Since the compound strip must pass through the cooling device, suitable clamping means must be provided for threading the strip through the device. The clamping means must be readily detachable from the strip after it is threaded through the cooling device in order that the strip may be conveyed to the insulating or jacketing apparatus.

An object of the invention is to provide new and improved clamps for connecting filamentary articles to moving traction elements.

Another object of the invention is to provide new and improved clamps for connecting strip material to an endless moving cable.

An apparatus embodying certain features of the invention which may be used to connect a filamentary article to a moving belt, comprises a pair of hingedly mounted jaws for engaging the end of a filamentary article to be connected to a moving traction element, means for camming the jaws tightly together on the filamentary article when the jaws are moved in the same direction as the moving traction element, and means for securing the jaws to the moving traction element.

A clear understanding of the invention will be had from a following detailed description of a specific embodiment thereof when read in conjunction with the appended drawings, in which:

Fig. 1 shows an apparatus for cooling strip material which is provided with a strip clamp embodying certain features of the invention;

Fig. 2 is an enlarged, plan view of a clamp which may be used for threading strip material through the cooling apparatus shown in Fig. 1;

Fig. 3 is a side elevation of the clamp shown in Fig. 2;

Fig. 4 is an enlarged, fragmentary view showing certain elements of the clamp shown in Fig. 3 in their open position;

2

Fig. 5 is a plan view showing certain elements of the clamp shown in Fig. 2 in their open position, and

Fig. 6 is a vertical sectional view taken along line 6—6 of Fig. 3.

Referring now to the drawings, and more particularly to Fig. 1, there is shown a compound strip cooling device 10 which comprises a pair of drums 11 and 12 suitably journaled in the cooling device and driven in the same direction by an electric motor 14 through gear reducers 15 and 16 and endless chain belts 20 and 21. An endless cable 23 travels in grooves 24—24 provided in the periphery of the drum 11 and grooves

25—25 provided in the periphery of the drum 12. The cable travels from a driven splicing roll 26 positioned at the entrance end of the cooling device 10 to a pair of driven rolls positioned adjacent to the exit end of the cooling device one of which rolls is shown in the drawing and indicated by the numeral 27. The drums 11 and 12 are positioned in the cooling device so that the grooves 24—24, in the drum 11, are staggered with respect to the grooves 25—25 provided in the drum 12.

The cooling device 10 is designed to draw a material strip 35 from the entrance end thereof adjacent to the roll 26 and pass it alternately over and under the drums 11 and 12, and finally discharge it from the exit end thereof adjacent to the roll 27. The strip 35 may be formed from a vulcanizable compound commonly used as an insulating covering or jacket on electrical conductors such as rubber and rubber-like compounds or it may be formed from various thermoplastic compounds used for the same similar purposes. The strip 35 is emerging from a strip-forming means associated with a conventional rubber mill or from a strip extruder, and in either case, the compound is at a substantially high temperature as it is formed into the strip 35.

As the strip 35 passes over the drums 11 and 12, it is subjected to a plurality of cold water sprays directed against the strip 35 by a plurality of perforated pipes 36—36 which are connected to a water supply pipe 37 which reduces the temperature of the strip to a safe value. As the strip passes under the drums it is submerged in cold water contained in the cooling device.

A guide plate 38 is positioned across the top of the drums as shown, and a similar plate (not shown) is positioned beneath the drums for guiding the strip 35 as it passes through the cooling device when the drums are rotated by the motor 14.

There is provided, a clamp, indicated generally

at 40 (Fig. 1), to which the present invention is directed, for threading the leading end of the strip 35 through the cooling device 10. The clamp 40 is designed to grip the leading end of the strip and the endless cable 23 at any point along the cable and pull the strip through the cooling device along the path of travel followed by the cable. The top plate 38 is provided with grooves 39-39 to receive the portion of the clamp 40, which is connected to the cable 23.

The clamp 40 is provided with jaws 41 and 42 which are hingedly mounted to each other by a pin 44. The jaw 41 is provided with elongated fingers 46-46 designed to intermesh with fingers 47-47 provided on the jaw 42. The fingers 46-46 and 47-47 converge toward each other, and the free ends thereof are turned upwardly and downwardly at 48, respectively, so as to engage a pin 50 positioned across the ends of parallel arms 51-51 secured to a body 52. This arrangement of the fingers 46-46 and 47-47 makes the jaws 41 and 42 slidably mounted on the pin 50, and, in addition, the pin 50 cams the jaws 41 and 42 to their closed position as the curved ends 48-48 engage the pin. When the jaws are slid to the left, as shown in Fig. 4, the jaws may be opened readily by pressing the fingers 46-46 downwardly and raising the fingers 47-47 upwardly. When the jaws are pulled to the right (Fig. 4), the pin 50 engages the underside of the fingers and forces them into their respective positions shown in Fig. 3 to close the jaws 41 and 42 on the strip 35. The free ends of the jaws 41 and 42 are provided with pointed teeth 55-55 which pierce the compound strip 35 when the jaws are closed.

The opposite end of the body 52 is provided with jaws 57 and 58 which are hingedly joined to each other in a plier-like manner by a pin 59. The free ends of the jaws 57 and 58 are provided with cable gripping members 60 and 61, respectively, having semi-circular grooves 62-62 provided in the opposed faces thereof and designed to fit the cable 23 (Fig. 6) when the jaws are closed. The jaws 57 and 58 have operating arms 64 and 65, respectively, which are provided with a slot 66. The slot 66 in the arm 64, and the slot 66 in the arm 65, slidably engage pins 67 and 68, respectively, spacedly positioned in the left end of the body 52. When the jaws are moved toward the body 52, the pins 67 and 68 coat with their respective slots to operate the arms and open the jaws 57 and 58 as seen in Fig. 5. When the jaws are moved away from the body 52 the arms are actuated by the pins to close the jaws and the grips 60 and 61 carried thereby tightly around the cable 23, as seen in Fig. 2.

Operation

The clamp 40 operates in the following manner to thread the strip 35 through the cooling device 10. The leading end of the strip 35, which is emerging from the suitable strip-forming means, is fed into the entrance end of the cooling device 10. The clamp 40 is positioned so that the teeth 55-55 of the jaws 41 and 42 may be closed on the end of the strip. The clamp then is moved in the direction in which the cable 23 travels through the cooling device to cause the pin 50 to cam the fingers 46-46 and 47-47 inwardly. This movement of the fingers causes the teeth 55-55 to close more tightly on the strip 35.

After the jaws are closed on the end of the strip 35, the jaws 57 and 58 are opened so that

the cable grips 60 and 61 may be positioned astride the cable 23. The jaws 57 and 58 are closed so that the cable grips 60 and 61 close around the cable 23. The motor 14 is energized to drive the drums 11 and 12, which in turn, draw the cable 23 along its path of travel. This movement of the cable causes the jaws 57 and 58 to close more tightly against the cable, and also causes the pin 50 to urge the fingers 46-46 and 47-47 closer together, and close the jaws 41 and 42 more tightly on the strip 35. The slots 66-66 are of such length that the pins 67 and 68 force the jaws 57 and 58 to close the grips 60 and 61 tightly around the cable before the pins reach the end of the respective slots.

When the clamp 40 carries the leading end of the strip to a point adjacent to the roll 21, the cable is stopped so that the clamp 40 may be removed from the strip and the cable. To remove the jaws 57 and 58 from the cable 23, the jaws are moved toward the body 52, which movement causes the pins 67 and 68 to spread the arms 64 and 65, and thereby open the jaws 57 and 58. When the jaws 57 and 58 are released from the cable 23, the body 52 is moved toward the end of the strip to disengage the pin 50 from the ends of the fingers 46-46 and 47-47. Then the fingers 46-46 are pressed downwardly and the fingers 47-47 are raised upwardly to actuate the jaws 41 and 42 and disengage the teeth 55-55 from the strip. The clamp 40 then is removed from the cooling device 10, and the motor 14 is energized to rotate the drums which will pull the strip through the cooling device. Low temperature water is supplied to the pipe 37 and the pipes 36-36 which spray the water on the strip 35 passing through the cooling device.

While the above-described clamp is particularly well adapted to thread strip material through a strip cooling device, it may be modified to grip various kinds of filamentary articles and attach them to a moving traction element or the like without departing from the spirit and scope of the invention.

What is claimed is:

A quickly detachable, flexible clamp for connecting the leading end of a strip of flexible material to a continuously advancing, endless cable used for threading such a strip through a tortuous path in a material treating apparatus, which comprises a substantially planar, U-shaped body, a pair of pivotally interconnected, plier-like levers pivotable about an axis perpendicular to the plane of the body, a pair of cooperating cable grippers pendently mounted on one end of the plier-like levers, each of said levers having an extension at the other end thereof provided with a camming slot formed therein, a pair of pins spacedly mounted at the closed end of the U-shaped body and received within the camming slots formed in the levers to slidably connect said levers to the body, said camming slots and pins cooperating so as to force the grippers into gripping engagement with a cable positioned therebetween when the body is urged axially away from the levers, a pair of relatively flat, cooperating jaws, means for hinging the jaws together intermediate their ends about a transversely disposed axis parallel to the plane of the body, strip-engaging teeth mounted on said jaws on one side of the hinge, said jaws having intermeshing extensions converging on the other side of the hinge, and a transversely disposed rod-like member slidably interposed between the hinge and the inter-

meshing ends of the converging extensions of the jaw, said rod-like member being mounted at its opposite ends between the parallel sides of the U-shaped body at the open end thereof, whereby when the body is urged axially away from the jaw elements the teeth are forced into engagement with a strip of material.
